Inventor:

George W. Smith
By Wright, Port attys.

UNITED STATES PATENT OFFICE.

GEORGE W. SMITH, OF DALLAS, TEXAS.

UNDERGROUND ELECTRIC RAILWAY.

SPECIFICATION forming part of Letters Patent No. 645,021, dated March 6, 1900.

Application filed August 23, 1899. Serial No. 728,201. (No model.)

To all whom it may concern:

Be it known that I, GEORGE W. SMITH, a citizen of the United States, residing at Dallas, in the county of Dallas and State of Texas, have invented certain new and useful Improvements in Underground Electric Railways, of which the following is a full, clear, and exact description, reference being had to the accompanying drawings, forming part of this specification.

One object of my invention is to provide an underground conduit in which is arranged the conductor or feed-wire from which the motors on the cars receive their power, together with means whereby the current of electricity is transferred from the wire or conductor to the motors.

A further object of my invention is to provide a trolley for underground electric railways with insulated brushes which will clear the tracks on which said trolley rides of all obstructions and which brushes will also effectually insulate all parts of the trolley, except the wheels, from the trolley-track.

To the above purposes my invention consists in certain novel features of construction and arrangement of parts, which will herein-after be more fully described and claimed.

In the drawings, Figure I is a transverse sectional view showing a railway-track, the conduit, the conductor and trolley therein, and the means employed for elevating the conductor and trolley. Fig. II is a longitudinal sectional view taken approximately on the line II II of Fig. I. Fig. III is a vertical sectional view taken on the indicated line III, III, Fig. II. Figs. IV and V are views in perspective of the individual members that comprise the brushes of the trolley.

Referring to the numerals on the accompanying drawings, 1 indicates the conduit, which is arranged between the track-rails 2, from the top of which conduit depend the hangers 3, to the lower ends of which are secured in any suitable manner the vertical members of a pair of inverted-L-shaped bars 4, on the horizontal members of which the brushes of the trolley ride. Held between the vertical members of these L-shaped bars 4 are the upper ends of a continuous flexible tube 5, on the interior of the bottom of which is arranged the conductor 6, the same being

oval in cross-section. Between the upper ends of this tube 5 are the contact-shoes 7, the same being in the form of plates with flat top surfaces, which surfaces occupy the same plane as do the top sides of the horizontal portions of the L-shaped bars 4, and integral with the lower ends of the shoes 7 are the transversely-arranged webs 8, the under sides 60 of which are concave. Between the meeting ends of the shoes 7 are arranged blocks 9 of insulating material, the same being held in place by bolts 10, which pass through the vertical members of the L-shaped bars 4 and 65 also through the upper ends of the tube 5.

Depending from the car-body and arranged for vertical movement relative thereto is a trolley-pole 11, the lower end of which carries a rectangular casing 12, in which is rotatably arranged a pair of trolley-wheels, the same riding directly upon the top surfaces of the shoes 7, and said trolley-wheels are suitably arranged in insulated bearings in the casing 12, and from the axles of said trolley-wheels suitable electric conductors are led to the motors carried by the car. An arm 13^a extends from the trolley-arm 11 to a point slightly below the plane occupied by the flexible tube 5, and a roller 13^b, having a concave 80 face, is rotatably arranged on the lower end of said arm 13^a, which roller normally engages against the under side of said flexible tube.

Arranged at the sides and at the ends of the casing 12 are the casings 14, the same being joined to one another in any suitable manner and provided with a sleeve 15, which passes around the part of the trolley-pole 11 adjacent to the housing 12. Secured to this sleeve 15 is the lower end of an arm 16, which extends upwardly into the car and by means of which the casings 14 are elevated when desired. Formed in the side walls of the casings 14 are the oppositely-arranged longitudinally-extending grooves 17, in which grooves 95 are seated the ends of the bars which carry the members forming the brushes of the trolley. These members (illustrated in Figs. IV and V) are alternately arranged in casings 14, and said members comprise rectangular bars 18 of insulating material, and from one set of said members depends a pair of metallic plates 19, and from the opposite set of said members depend single plates 20 of suitable insulating

material. These individual members are alternately arranged in casings 14, with the ends of the bars 18 in the grooves 17, and when in position the lower ends of the plates 19 and 20 5 occupy the same horizontal plane and are intended to ride directly on top of the horizontal portions of the bars 4 and also on top of the surfaces of the shoes 7.

The operation is as follows: The motorman 10 or person in charge of the car by the use of the proper levers elevates the arm 13^a, carrying the grooved roller 13^b, and in so doing brings the conductor 6 into electrical contact with the concave under sides of the shoes 7, the 15 positions of said conductor and flexible tube at the time of the contact being shown by dotted lines in Figs. II and III, and as soon as this contact is made the current of electricity will pass from the conductor 6 upwardly through 20 the shoe or shoes with which it is in contact to the trolley-wheel 13 and thence through the proper conductors to the motors. As the car advances the conductor is successively brought into contact with the shoes 7, and at 25 no time is said conductor in contact with more than two of said shoes. Therefore the loss or waste of the current of electricity will be reduced to a minimum. As the car moves forward the metallic plates 19 and plates 20, of 30 insulating material, will ride upon the top surfaces of the horizontal members of the bars 4 and also upon the contact-surfaces of the shoes 7 and all dust, water, and other foreign matter will be thoroughly and efficiently removed 35 from these surfaces.

The motorman can at any time desired elevate the casings 14 to the position shown by dotted lines, Fig. III, by merely raising the arm 16. 40 By forming the conductor 6 oval in cross-section it is rendered very flexible in its vertical movement when being brought into contact with the shoes, and at the same time it is stiffened against lateral movement or play 45 within the flexible tube 5.

I claim as my invention—

1. In an underground electric railway conduit, a track therein, contact-shoes arranged in said track, which shoes are insulated from 50 said track and from each other, a conductor suspended beneath the shoes, means carried by the car-body for bringing the conductor into contact with the shoes, a trolley carried by the car and riding upon the track and 55 brushes surrounding the contact portion of the trolley substantially as specified.

2. In an underground electric railway a conduit, a track therein, contact-shoes arranged in said track, which shoes are insulated from 60 said track and from each other, a conductor suspended beneath the shoes, means carried by the car-body for bringing the conductor into contact with the shoes, a trolley carried

by the car and riding upon the track, brushes surrounding the contact portion of the trolley, and means whereby said brushes are elevated independent of the trolley, substantially as specified. 65

3. In an underground electric railway a conduit, a track therein, contact-shoes arranged in said track, a conductor suspended beneath the shoes, means carried by the car-body for bringing the conductor into contact with the shoes, a trolley carried by the car and riding upon the track, a plurality of casings 75 surrounding said trolley and alternately-arranged metallic and insulating plates, the same forming brushes, and which are carried in the casings substantially as specified.

4. In an underground electric railway the 80 combination with a trolley of a plurality of brushes surrounding said trolley, substantially as specified.

5. In an underground electric railway the 85 combination with a trolley of a plurality of brushes surrounding said trolley, which brushes comprise alternately-arranged metallic and insulating plates, substantially as specified.

6. In an underground electric railway the 90 combination with a trolley of a plurality of brushes surrounding said trolley, and means whereby said brushes are elevated independent of the trolley, substantially as specified.

7. In an underground electric railway the 95 combination with a trolley of a plurality of casings surrounding the trolley, which casings are united, a plurality of alternately-arranged metallic and insulating plates positioned in said casings, and means whereby the casings are elevated independent of the trolley, substantially as specified.

8. In an underground electric railway, the combination with a plurality of contact-shoes, the under sides of which are concaved, of a 10 longitudinally-extending feed-wire oval in cross-section and horizontally arranged immediately beneath said contact-shoes, and means for bringing said feed-wire and contact-shoes into contact; substantially as specified. 11

9. In an underground electric railway, the combination with a continuous flexible hanger of a plurality of contact-shoes arranged in the upper portion of said hanger, the under 11 sides of which shoes are concaved, a feed-wire oval in cross-section and horizontally arranged and held by the hanger immediately beneath said contact-shoes, and means whereby said feed-wire is brought into contact with 12 the concaved undersides of the contact-shoes; substantially as specified.

G. W. SMITH.
